FLUID DISPENSER

Harold N. Perelson, Huntington Park, Calif.

Application June 13, 1942, Serial No. 446,987

5 Claims. (Cl. 215—47)

My invention relates to improvements in fluid dispensers for vials or other containers of multiple doses of a therapeutic or similar solution, such dispenser being of the type disclosed in my application for U. S. Letters Patent Serial Number 358,057, filed September 24, 1940, now Patent No. 2,289,677, dated July 14, 1942.

Administration of doses of therapeutic substances and the like from multiple dose containers in usual practice involves the use and handling of two needles in combination with the syringe; a large bore needle for extraction of the fluid from the container and the substitution of a fine needle therefor for the injection operation. Use of the large bore needle permits charging the syringe without undue loss of time, whereas the fine bore needle is desirable for administration of the dose.

It is apparent that handling of two needles doubles the necessity for exercising precautions requisite for antiseptic operation of the combination as a therapeutic instrument.

An object of the present invention is to provide a dispenser of the character described, wherein operative movement of the dispenser needle is precisely governed to provide for substantially complete utilization of the container contents without the exercise of precisional manipulation by the operator.

A further object is to provide a closure for the container and mounting for the needle sufficiently elastic to insure easy operation together with durable qualities affording repetitional intrusion into and retraction of the needle from the container interior and conjointly embody sufficient rigidity of structure to provide the requisite firmness necessary to hold the needle in place during manipulation of the attached syringe.

Another object is to provide a dispenser such as described wherein the body portion; made of elastic material such as rubber, embodies not only the requisites above defined but in addition is devised to afford a disposition of parts as to relative all thickness and arrangement such as conforms to the practical requirements of the molding arts, for example, the removal of "forms" without mutilation of the product.

With the above and other objects in view the invention consists in the novel construction and combination of parts hereinafter described, illustrated in the accompanying drawing, and set forth in the claims hereto appended, it being understood that various changes in form, proportion, size and minor details of construction with-

in the scope of the claims may be resorted to without departing from the spirit or sacrificing any of the advantages of the invention.

Referring to the drawing:

Figure 1 is an elevational view of the dispenser of my invention in relation to and as affixed to a vial.

Figure 2 is an enlarged top plan view of my dispenser shown in Figure 1.

Figure 3 is a part sectional, part elevational view taken on the plane of line 3—3 of Figure 2.

Figure 4 is a sectional view similar to Figure 3 showing the dispenser parts in operative position and conjunction with a syringe shown in fragmentary elevation.

Referring to the drawing more specifically it is seen that one embodiment of my improved dispenser generally includes an especially constructed stopper A of elastic material such as rubber or a rubber substitute, formed with a chamber B in which a hollow needle C is disposed so that when the needle is depressed the point thereof will penetrate one of the walls of the chamber to gain access to the contents of the bottle D. The needle is exposed for connection with a syringe E whereby the contents of the bottle may be withdrawn. Normally the stopper supports the needle so that the point lies within the chamber and the stopper will provide a tight closure for the bottle, a "puncture" previously made by the needle being closed due to the elasticity of the material.

One of the advantageous features of the present invention is that of reinforcing the outer end of the stopper by means of an integral marginal flange 1 which extends outwardly from and in the present instance surrounds the outer wall 2 of the stopper. The flange 1 provides in effect a circumferential elastic force radially active to return the outer wall 2 to its normal position, while the hub 3 of the needle C is gripped and held in an apertured boss 4 formed at the center of the wall.

Shoulders 5 and 6 on the hub together with the boss constitute a means for holding the needle within chamber C and normally spaced inwardly from the inner wall 7 of the stopper, it being noted that the chamber B extends between the walls 2 and 7. This holding means also holds the needle against being forced through the outer wall so that when it is depressed the outer wall will stretch or yield inwardly as shown in Figure 4 and allow the point of the needle to penetrate the inner wall 7. In this connection it should be noted that as another improvement the stopper

A is provided on the wall of the chamber B with an annular stop shoulder 8 adapted to engage the shoulder 6 on the hub of the needle to limit the inward thrust of the needle as shown in Figure 4. This feature providing for relatively precise adjustment of the point end of the needle as just penetrative of the inner wall 7 for substantially complete extraction of the container contents.

It should also be noted that the stopper is formed with an enlarged head portion 9 in which is formed the enlarged outer end of the chamber B in such manner that the walls of the head also the flange 1 are thicker than annular portions of the outer wall 2 which surrounds the boss 4, whereby the outer end of the stopper will be comparatively rigid while the wall 2 is highly elastic and may be stretched inwardly to allow the needle to penetrate the inner wall 7. However, the outer wall has sufficient body and rigidity to normally support and retain the needle with its point spaced outwardly from the inner wall 7 and to hold the needle steady for connection with the syringe.

The rigidity and stability provided at the outer end of the stopper by means of the flange 1 and the particular formation of the head 9, lends the firmness necessary to make possible an easy attachment and removal of the needle; also, a ready and easy connection of the syringe to the needle, yet provides the desired flexibility of the outer wall 2 to enable easy penetration of the stopper. Ready access to the boss 4 for insertion of the needle hub is provided by having the outer ends of the boss and flange substantially co-planar.

Moreover, the particular construction of the stopper as here provided makes possible a practicable molding operation and facilitates removal of the "forms" without mutilation of the stopper.

I claim:

1. In a dispenser for a bottle or the like, a stopper of resilient material having resilient inner and outer end walls and a chamber between said walls, a reinforcing flange on said stopper extending substantially rightangularly from said outer end wall at the periphery thereof, a hollow needle extending through said outer end wall into said chamber; and means supporting said needle on said outer end wall with its point normally spaced outwardly from and adapted to penetrate said inner end wall when the needle is pushed inwardly and the outer end wall responsive yields inwardly.

2. In a dispenser for a bottle or the like, a stopper of resilient material having resilient inner and outer end walls and a chamber between said walls, a reinforcing flange on said stopper extending outwardly from said outer end wall, a hollow needle extending through said outer end wall into said chamber, means sup-

porting said needle on said outer end wall with its point normally spaced outwardly from and subject to penetrating said inner wall when the needle is pushed inwardly and the outer wall responsive yields inwardly, a stop shoulder on said needle and a stop shoulder on said stopper within said chamber intermediately positioned between said inner and outer walls for limiting the inward thrust of said needle.

3. In a dispenser for a bottle or the like, a stopper of resilient material having resilient inner and outer end walls and a chamber between said walls, a reinforcing flange on said stopper extending outwardly from said outer end wall, a hollow needle extending through said outer end wall into said chamber; means supporting said needle on said outer end wall with its point normally spaced outwardly from and subject to penetrating said inner end wall when the needle is pushed inwardly and the outer wall responsive yields inwardly; and co-operating stop shoulders within the chamber and on said needle adapted to engage one another upon a predetermined inward thrust of the needle.

4. In a dispenser for a bottle or the like, a stopper of resilient material having resilient inner and outer end walls and provided with a chamber between said walls, a hollow needle extending through said outer end wall and into said chamber, means for fixing the needle to said outer wall so that the outer wall will yield responsive to inward and outward movement of the needle to cause the needle to penetrate and withdraw from penetration of said wall respectively, and stop members on said needle and within the chamber adapted to engage one another to limit the inward thrust of the needle.

5. In a dispenser for a bottle or the like, a stopper of resilient material having a resilient outer end wall adapted to be inwardly stretched and returned to its normal position, and a resilient inner end wall adapted to be penetrated, a marginal flange on said stopper extending substantially rightangularly to, surrounding and reinforcing said outer end wall, said stopper having a chamber between said walls, a hollow needle extending through said outer end wall into said chamber, means for securing the needle to the outer wall so that said wall will stretch inwardly responsive to an inward thrust of the needle and permit the needle to penetrate said inner wall and will be retracted to normal position responsive to withdrawal of the needle from said penetrating position and an apertured boss formed on and reinforcing the center of said outer end wall and receiving the needle in the aperture thereof, said boss being normally substantially co-planar at its outer end with the outer end of said flange.

HAROLD L. PERELSON.
